US00D561129S

(12) **United States Design Patent** (10) Patent No.: **US D561,129 S**
Hsiung (45) Date of Patent: **** Feb. 5, 2008**

(54) **PORTABLE WIRELESS DIGITAL LCD TELEVISION**

(75) Inventor: **Chen Kuo Hsiung**, Laguna (HK)

(73) Assignee: **Silicon Pyramid Electron, Ltd.**, Kowloon (HK)

(**) Term: **14 Years**

(21) Appl. No.: **29/250,074**

(22) Filed: **Nov. 1, 2006**

(30) **Foreign Application Priority Data**

Aug. 8, 2006 (CN) 2006 3 0067886

(51) **LOC (8) Cl.** **14-03**

(52) **U.S. Cl.** **D14/126**
